PROTECTIVE SYSTEM FOR ELECTRIC VALVE TRANSLATING APPARATUS

Filed April 7, 1938

Fig. 1.

Fig. 3.

Fig. 2.

The diagram illustrates a three-phase star connection. A vertical line labeled "STARTING" extends downwards from the center point O. Three lines branch out from O to points A, B, and C, representing the three phases. Point A is at the top, B is in the middle, and C is at the bottom. From point A, a line extends to point D, which is located to the right of point C. The angle between the line OA and the line AD is labeled "135°". A curved arrow labeled "OVERLOAD" points from point D towards point C. A curved arrow labeled "FULL LOAD" points from point C towards point B.

PROTECTIVE SYSTEM FOR ELECTRIC
VALVE TRANSLATING APPARATUSErnst F. W. Alexanderson, Schenectady, N. Y.,
assignor to General Electric Company, a corporation of New York

Application April 7, 1938, Serial No. 200,813

15 Claims. (Cl. 175—363)

My invention relates to electric valve circuits and more particularly to protective systems for electric valve apparatus of the type employing ionizable mediums such as gases or vapors.

- 5 In the use of electric valve apparatus, particularly electric valves employing ionizable mediums, it has been found that it is desirable to delay the application of load to the electric valves for a predetermined time to permit the cathode to attain 10 a temperature sufficiently great to emit the required electron current. If the load current, or in other words the anode-cathode current, is increased to a value beyond that corresponding to the cathode temperature, there will be a tendency 15 to pull relatively large portions of the electron emitting surface away from the cathode, thereby reducing the useful life of the valve. In addition, it is important in electric valve circuits to maintain the temperature of the electric valve means within a predetermined range of values 20 so that the life of the electric valve means is not unreasonably shortened. Heretofore, the prior art arrangements have increased the excitation of the cathode or the cathode heating element as the anode-cathode current increased 25 in order that the electron emission be commensurate with the load imposed on the electric valve means. Where electric valve means employing ionizable mediums are involved, considerable heating of the cathode or the cathode heating element is caused due to the anode-cathode current. This heating, in a general way, is due primarily to the positive ion bombardment caused by the conduction of the anode-cathode current. 30 In view of these factors, I have found that there is a decided need for new and improved electrical control circuits for electric valve means whereby the temperature of the electric valve means is maintained within a reasonable and safe range of values during operation. 35 It is an object of my invention to provide new and improved electric valve circuits. It is another object of my invention to provide new and improved protective systems for electric valve translating apparatus. 40 It is a further object of my invention to provide new and improved protective systems for electric valve apparatus of the type employing ionizable mediums and in which the energization of the cathode heating element is varied as the anode-cathode current changes. 45 In accordance with one of the illustrated embodiments of my invention, I provide a protective system for electric valve apparatus in which a cathode heating element is initially energized 50 by a relatively large current and in which the cathode heating element is energized by currents which decrease in value from no load value of the anode-cathode current. The cathode heating element circuit includes a source of alternating voltage of substantially fixed phase and magnitude and also includes a second source of alternating voltage of fixed phase but displaced relative to the voltage of the first source. The second source is preferably displaced by 135 electrical degrees relative to the voltage of the first source and varies in magnitude in accordance with the anode-cathode current of the electric valve means. The resultant voltage impressed across the terminals of the cathode heating element is therefore maximum at no load, and minimum at normal or full load, having progressively decreased in value from the no load to full load, and progressively increases in value for values of anode-cathode current above the full load 20 value. 55 In accordance with another illustrated embodiment of my invention, the progressive decrease in energization of the cathode heating element of an electric valve means is obtained by employing a saturable inductive reactance which is connected in series relation between a source of alternating current and the cathode heating element. The saturable inductive reactance includes a variable impedance winding which controls the resultant voltage impressed across the cathode heating element, a unidirectional magnetizing winding, and a third winding which is energized in accordance with the anode-cathode current of the electric valve means and which controls the resultant impedance of the variable impedance winding. 60 In accordance with a still further feature of one embodiment of my invention, I provide a protective system for electric valve apparatus having an anode, a cathode, a heating element for the cathode, and a control member which controls the current conducted by the electric valve means. I provide an excitation circuit for controlling the voltage impressed on the control member and which comprises a phase shifting device of the rotary type having a movable element. There is provided restraining means to prevent operation of the movable element and hence to prevent increase of the anode-cathode current of the electric valves for a predetermined time after the energization of the cathode heating element, thereby affording sufficient time for the cathode to attain a sufficiently high operating temperature. The restraining means may include a 65

plurality of electro-responsive relays which control the restraining means so that it may be moved progressively in a direction to increase the anode-cathode current of the electric valves in direct proportion to the period of energization of the cathode heating elements and after the expiration of the initial heating period. The control circuit which electrically energizes the plurality of electroresponsive relays comprises an electric valve of the high vacuum type which comprises a filamentary cathode which is energized simultaneously and concurrently with the cathode heating elements of the main electric valves which are to be protected.

15 For a better understanding of my invention, reference may be had to the following description taken in connection with the accompanying drawing and its scope will be pointed out in the appended claims.

20 Fig. 1 diagrammatically illustrates an embodiment of my invention as applied to an electric valve translating system including electric valve means of the type employing an ionizable medium; Fig. 2 represents certain operating characteristics thereof, and Fig. 3 diagrammatically illustrates a still further embodiment of my invention in which restraining means is associated with the excitation circuit of the electric valves to control the rate at which the anode-cathode current may be increased immediately after the initial energization period of the cathode heating elements.

25 Referring now to Fig. 1 of the accompanying drawing, my invention is diagrammatically illustrated as applied to an electric valve translating circuit for transmitting power between an alternating current circuit 1 and a direct current load circuit 2 which may include an armature circuit 4 of a direct current motor 3. Direct current motor 3, of course, may include a field winding 5 which is energized from a direct current source 6 through a rheostat or adjustable resistance 7. Electric translating apparatus is interposed between the circuits 1 and 2 and 30 includes a transformer 8 having primary windings 9 and secondary windings 10, and also includes electric valve means 11, 12 and 13 which are preferably of the type employing an ionizable medium such as a gas or a vapor. Each 35 of the electric valves 11-13 includes an anode 14 and a hot or thermionic cathode 15, a cathode heating element 16, and may include a control member 17. A suitable circuit interrupting means 18 is interposed between the alternating 40 current circuit 1 and the transformer 8 and includes an armature member 19, a closing coil 20 and a trip coil 21.

45 To energize the cathode heating elements 16 and to control the current supplied thereto in accordance with the load transmitted by the translating apparatus or to control the current supplied to the heating elements in accordance with the anode-cathode current of the electric valve means, I provide a cathode heating circuit 22 which includes a source of alternating voltage 23 which may be obtained from the alternating current circuit 1 through a transformer 24 and a switch 25. The cathode heating circuit 22 also includes a second source of alternating voltage which varies in magnitude in accordance with the anode-cathode current of the electric valve means 11-13, or in accordance with the current transmitted by the translating apparatus. The second alternating voltage is introduced into the cathode heating circuit 22 by

way of an impedance element such as a resistance 26. To energize the resistance 26 in accordance with the anode-cathode circuit of the electric valves 11-13, I employ a suitable means such as current transformer 27. I interpose 5 between the current transformer 27 and the resistance 26 a suitable phase shifting arrangement such as a rotary phase shifter 28 which is initially positioned to adjust the phase of the second alternating voltage relative to the first. 10 I have found that satisfactory control of the energization of the cathode heating elements 16 is obtained when the second alternating voltage provided across the terminals of resistance 26 is displaced substantially 135 electrical degrees 15 with respect to the source 23 of alternating voltage.

I provide a timing circuit 29 which is energized simultaneously with the closure of the switch 25 to effect closure of the circuit breaker 18 a predetermined time after the switch 25 has been closed so that there is afforded ample time for the cathode 15 to attain a safe operating temperature. The timing circuit 29 comprises a timing element such as an electric valve 30 25 of a high vacuum type having an anode 31 and a filamentary cathode 32. The electric valve 30 is designed so that its cathode temperature-time characteristic establishes the interval of time required for the proper preheating of the cathodes 15 of electric valves 11-13. The filamentary cathode 32 is connected to be energized from the cathode heating circuit 22 through a transformer 33. The control electric valve 30 effects 30 energization and operation of a relay 34 which includes an actuating coil 35, a pair of stationary contacts 36 and 37 and cooperating movable contacts 38 and 39. A capacitance 40 may be connected across coil 35 so that a substantially constant unidirectional current is transmitted to 40 the coil 35. Contacts 37 and 39 effect energization of the closing coil 20 of the circuit breaker 18 from a suitable source of current such as a battery 41. Contacts 36 and 38 effect energization of an actuating coil 43 of a time delay relay 42 which is employed to connect the rotary phase shifter 28 to the resistance 26. By employing a time delay relay 42, the resultant voltage impressed across the terminals of cathode heating element 16 is not decreased until after the expiration of a predetermined interval of time to insure sufficient initial heating of the cathodes 15.

The operation of the embodiment of my invention shown in Fig. 1 will be explained by 55 considering the system during the starting operation when it is desired to subsequently effect energization of the direct current circuit 2 from the alternating current circuit 1. Circuit breaker 18 and switch 25 are initially in the open circuit 60 positions. Upon the closure of switch 25, the cathode heating circuit 22 will be energized and the voltage of that circuit will be that provided by the source 23 which in turn is supplied by transformer 24. As soon as the switch 25 is 65 closed a relatively large current is transmitted to the cathode heating elements 16. Current is also supplied to the timing circuit 29. As soon as the cathode 32 of the control electric valve 30 reaches a temperature sufficiently high to pass 70 an appreciable anode-cathode current, actuating coil 35 of relay 34 will be energized, effecting closure of contacts 36, 38, and 37, 39. This time interval, of course, is preestablished so that the cathodes 15 of electric valves 11-13 attain a 75

safe operating temperature. Upon the closure of the relay 34, closing coil 20 of circuit breaker 18 is energized to connect the transformer 8 to the alternating current circuit 1. Concurrently with this operation, the operating coil 43 of the time delay relay 42 is energized and after a predetermined time the relay 42 is moved to the closed circuit position, connecting the phase shifter 23 to the resistance 26. Prior to the time of the closure of the relay 42, the current transmitted to the cathode heating elements 16 is maximum. However, after the closure of the relay 42, the cathode heating current varies with the load and progressively decreases in magnitude from a maximum value at no load to a minimum value at full load, thereby reducing the amount of current required to operate the electric valves 11-13 under full load conditions. This may be accomplished without sacrificing the operating characteristics and without shortening the life of the tubes since an appreciable heating of the cathodes 15 occurs due to the anode-cathode currents conducted by the electric valves.

25 A better understanding of the manner in which the cathode heating current varies in response to changes in the anode-cathode current may be obtained by reference to the operating characteristics shown in Fig. 2 where the vector OA represents the voltage of source 23 and the vectors AE, AC, and AD represent the voltages appearing across the terminals of resistance 26 under various load conditions. Accordingly, vectors OA, OB, OC and OD represent the resultant voltages impressed across the terminals of the cathode heating element under corresponding conditions and hence represent the magnitudes of the currents transmitted to the anode-cathode elements under these conditions. It will be noted that initially the energization of the cathode heating elements is maximum, corresponding to vector OA, and that the energization thereof is decreased as the load increases from no load to normal or full load. Furthermore, it will be noted that the energization of the cathode heating elements 18 progressively increases in the overload region, i. e., in the region above normal or full load.

In Fig. 3, there is shown a further embodiment of my invention in which a direct current circuit 44 is energized from an alternating current circuit 45 through a transformer 46 having primary windings 47, secondary windings 48 and electric valve means 49, 50 and 51, which electric valve means 49-51 is of the type employing an ionizable medium and which comprises an anode 52, a cathode 53, a cathode heating element 54 and a control member or grid 55.

A switch 56 is interposed between the alternating current circuit 45 and the transformer 46 and effects energization of the cathode heating elements 54 through a transformer 57. To control the magnitude of the current transmitted to the heating elements 54 in accordance with the anode-cathode current of the electric valves 49-51, I employ a saturable inductive reactance 58 comprising a variable impedance winding 59 which is connected in series relation with the primary winding of transformer 57, a unidirectional magnetizing winding 60, and a control winding 61 which is energized in accordance with the anode-cathode current of valves 49-51. The unidirectional magnetizing winding 60 may be energized with direct current from any suitable source such as from a direct current source 62

through a switch 63 which is arranged to be operated simultaneously with the switch 56.

I provide an excitation circuit 64 for energizing the grids 55 of electric valves 49-51 to control the current conducted by these electric valves. The excitation circuit 64 includes a suitable means for controlling the voltages impressed on grids 55, such as a rotary phase shifter 65, including a stationary winding 66 and a relatively movable winding 67 which controls the phase of the alternating voltages impressed on grids 55 relative to the anode-cathode voltages of the electric valves 49-51. A battery 68 may be employed to impress on the grids 55 a unidirectional biasing potential. I provide a suitable actuating member, such as a handle 69, for moving the winding 67 relative to the winding 66 to control the phase of the alternating voltages impressed on grids 55. As a means for restraining the movement of the handle 69 for a predetermined time after the energization of the cathode heating elements 54, I provide a device 70 comprising a plurality of detent members 71 and 72 and associated electroresponsive actuating devices 73 and 74. The detent members 71 and 72 may be spring biased to engage an extension 75 of the actuating handle 69 so that the handle 69 may not be moved unless the electroresponsive devices 73 and 74 are energized. To permit progressive movement of the actuating member 69 in direct relation to the period of energization of cathode heating elements 54 after the expiration of an initial preheating period, the electroresponsive devices 73 and 74 may be arranged to be selectively energized. That is, the electroresponsive devices 73 and 74 may be arranged so that the detent members 71 and 72 thereof are retarded for different values of current conducted through the actuating coils thereof. The restraining device 70 includes a spring biased armature 76 which tends to return the actuating member 69 to the initial vertical position when reset coil 77 is deenergized. This reset action may be effected by any suitable means and is diagrammatically illustrated as comprising a pawl and ratchet mechanism 78 and a sliding connection 79. The armature 76 returns the winding 67 to a position which maintains electric valves 49-51 non-conductive.

I provide a control and timing circuit 80 which effects selective energization of the electroresponsive devices 73 and 74 and which controls these devices in response to the period of energization of the cathode heating elements 54. Control circuit 80 comprises an electron discharge device 81 of the high vacuum type including a filamentary cathode 82 which is connected to be energized concurrently and simultaneously with the energization of the cathode heating elements 54 from the alternating current circuit 45 through a transformer 83. The electron discharge device 81 is designed so that it affords an appreciable interval of time for the energization of the cathode heating elements 54 of electric valves 49-51 before it permits the movement of 85 the actuating member 69.

The operation of the embodiment of my invention shown in Fig. 3 will be explained by considering the system under starting conditions when it is desired to effect energization of the 70 direct current circuit 44 from the alternating current circuit 45. Upon the closure of switches 56 and 63, current is supplied to the cathode heating elements 54 of electric valves 49-51 and heating current is also supplied to the filament- 75

5 tary cathode 82 of the discharge device 81. The control circuit 83, which is also a timing circuit, will delay the transmission of current from the direct current source 62 to electroresponsive devices 73 and 74 until the cathodes 53 of electric valves 49—51 have attained a safe operating value. After the expiration of a predetermined time interval, current will be transmitted by the electron discharge device 81 to effect the movement of the detent member 71 associated with the electroresponsive devices 73 out of engagement with the extension 75 so that the actuating handle 69 may be moved to the dotted position. By such movement, the phase of the voltages 10 impressed on the control members 55 is advanced relative to the anode-cathode voltages so that the current conducted by the electric valves 49—51 is increased by increments from a zero value to a predetermined value corresponding to the movement 15 of the actuating handle 69. Subsequently, the current transmitted by the electron discharge device 61 increases to a still greater value, effecting movement of the detent member 72 out of engagement with the extension 75 so that the 20 current conducted by electric valves 49—51 may be still further increased. Of course, to permit this movement of actuating member 69, the coil 77 is energized moving the armature 76 to the position shown. If the source of alternating 25 voltage fails, the armature 76 will be moved to the right-hand position, returning the actuating member 69 to the vertical initial position in which electric valves 49—51 are controlled to conduct substantially no current.

30 35 The saturable inductive device 58 controls the resultant voltage impressed across the primary winding of the transformer 57 in accordance with the anode-cathode current of electric valves 49—51. The windings 60 and 61 of the saturable inductive reactance are oppositely disposed and by virtue of this fact the heating element current is maximum when the anode-cathode current of the inductive reactance of winding 59 is minimum. As the anode-cathode current increases, inductive reactance of the winding 59 increases to decrease the resultant voltage impressed on transformer 57. In this manner, at low values of anode-cathode current, a relatively large current is transmitted to the cathode heating elements and as the anode-cathode current increases, the cathode heating current is progressively decreased in value.

40 45 50 55 60 While I have shown and described my invention as applied to a particular system of connections and as embodying various devices diagrammatically shown, it will be obvious to those skilled in the art that changes and modifications may be made without departing from my invention, and I, therefore, aim in the appended claims to cover all such changes and modifications as fall within the true spirit and scope of my invention.

What I claim as new and desire to secure by Letters Patent of the United States, is:

1. In combination, an alternating current circuit, a load circuit, electric translating apparatus connected between said circuits and comprising electric valve means having an anode, a cathode and a heating element for said cathode, a circuit for energizing the cathode heating element comprising a source of alternating current for transmitting a relatively large current to the cathode heating element to increase the temperature of the cathode to a suitable value for operation, means for energizing the anode-cathode circuit of said electric valve means, and time delay

means responsive to the energization of the cathode heating element circuit for reducing the value of the current supplied to said cathode heating element as the current transmitted by said translating apparatus increases.

2. In combination, a supply circuit, a load circuit, electric translating apparatus connected therebetween and comprising an electric valve means having an anode, a cathode and a heating element for said cathode, means for supplying a relatively large current to the cathode heating element for a predetermined interval of time to increase the temperature of said cathode to place said electric valve means in condition for operation, means for energizing the anode-cathode circuit of said electric valve means at the expiration of said interval, and means responsive to the current transmitted by said translating apparatus for progressively decreasing the value of the current supplied to the cathode heating element as the current transmitted by said translating apparatus increases from no load to full load value.

3. In combination, a supply circuit, a load circuit, electric translating apparatus connected therebetween and comprising an electric valve means having an anode, a cathode and a heating element for said cathode, means for supplying a relatively large current to the cathode heating element for a predetermined interval of time to increase the temperature of said cathode to place said electric valve means in condition for operation, means for energizing the anode-cathode circuit of said electric valve means at the expiration of said interval, means for energizing the cathode heating element comprising a source of alternating voltage, and means responsive to the current transmitted by said translating apparatus for impressing on said cathode heating element a resultant voltage the magnitude of which varies in accordance with the load transmitted by said translating apparatus.

4. In combination, an alternating current circuit, a load circuit, electric translating apparatus connected between said circuits and comprising electric valve means having an anode, a cathode and a heating element for said cathode, circuit interrupting means for connecting said translating apparatus to said alternating current circuit and including a closing coil, a circuit for energizing the cathode heating element and comprising a source of alternating current, time delay means responsive to the energization of the cathode heating circuit for initiating energization of said closing coil, and means responsive to said time delay means for introducing into the cathode heating circuit an alternating voltage which varies in accordance with the current transmitted by said electric translating apparatus to control the current supplied to said cathode heating element.

5. In combination, an electric valve means having an anode, a cathode and a heating element for said cathode, means for energizing the cathode heating element comprising a source of alternating voltage, and means for impressing on said heating element a resultant voltage which varies in magnitude in accordance with the anode-cathode current of said electric valve means comprising a source of alternating voltage displaced in phase relative to the voltage of said first mentioned source and being variable in magnitude in accordance with the anode-cathode current of said electric valve means.

6. In combination, an electric valve means hav-

ing an anode, a cathode and a heating element for said cathode, means for energizing the cathode heating element comprising a source of alternating voltage, and means for controlling the resultant voltage impressed on said cathode heating element in accordance with the current of the anode-cathode circuit of said electric valve means and comprising a second source of alternating voltage displaced substantially 135 electrical degrees with respect to the voltage of said first mentioned source and which varies in magnitude in accordance with the anode-cathode current so that the voltage impressed across said heating element is maximum at no load and minimum at full load.

7. In combination, an electric valve means having an anode, a cathode and a heating element for said cathode, means for energizing the cathode heating element comprising a source of alternating voltage, and means for controlling the resultant voltage impressed across said cathode heating element comprising a second source of alternating voltage connected in series relation with the first mentioned source and which varies in accordance with the anode-cathode current of said electric valve means and which is displaced substantially 135 electrical degrees relative to the voltage of said first mentioned source so that the resultant voltage impressed across said cathode heating element is maximum at no load, minimum at the normal full load current of said electric valve means and is progressively increased for anode-cathode currents above the full load value.

8. In combination, an alternating current circuit, a load circuit, electric translating apparatus connected between said circuits and including an electric valve means having an anode, a cathode and a heating element therefore, switching means for connecting said translating apparatus to said alternating current circuit and including a closing coil, a circuit for energizing said heating element, a source of alternating voltage for energizing the heating element circuit, time delay means for energizing said closing coil a predetermined time after the energization of the cathode heating circuit, means responsive to the current consumed by said translating apparatus for introducing into the cathode heating circuit a component of voltage of fixed phase displacement and variable magnitude relative to the voltage of said source and comprising an impedance element connected in series relation with said source and a phase shifting circuit for controlling the phase of the voltage appearing across the terminals of said impedance element, and means responsive to the operation of said time delay means for connecting said phase shifting circuit to said impedance element a predetermined time after the operation of said time delay means.

9. In combination, a supply circuit, a load circuit, electric translating apparatus connected between said circuits and comprising an electric valve means having an anode, a cathode, a heating element for said cathode and a control member, an excitation circuit for energizing said control member comprising control means for impressing thereon a voltage to control the current conducted by said electric valve means, and means responsive to the period of energization of said heating element for controlling said control means to limit the rate of increase of the current conducted by said electric valve means.

10. In combination, an alternating current circuit, a load circuit, electric translating apparatus connected between said circuits and including an electric valve means having an anode, a cathode, a heating element for said cathode and a control member for controlling the conductivity thereof, an excitation circuit for energizing said control member to effect control of the magnitude of the current conducted by said electric valve means and including means for controlling the voltage impressed on said control member, and means associated with said last mentioned means to prevent operation thereof for a predetermined time after the energization of said translating apparatus.

11. In combination, an alternating current circuit, a load circuit, electric translating apparatus connected between said circuits and comprising an electric valve means including an anode, a cathode, a heating element for said cathode and a control member, switching means for connecting said translating apparatus to said alternating current circuit, an excitation circuit for energizing said control member to control the current conducted by said electric valve means and including a device for controlling the voltage impressed on said control member, means for operating said device, and means for preventing the operation of said last mentioned means for a predetermined time after the energization of said translating apparatus by the closure of said switching means.

12. In combination, an alternating current supply circuit, a load circuit, electric translating apparatus connected between said circuits and comprising an electric valve means having an anode, a cathode, a heating element for said cathode and a control member, an excitation circuit for energizing said control member to control the magnitude of the current conducted by said electric valve means and including a phase shifting device for controlling the phase of the voltage impressed on said control member relative to the anode-cathode voltage, and means for preventing operation of said phase shifting device for a predetermined interval of time after the energization of said translating apparatus.

13. In combination, an alternating current supply circuit, a load circuit, electric translating apparatus connected between said circuits and comprising an electric valve means having an anode, a cathode, a heating element for said cathode and a control member, an excitation circuit for energizing said control member to control the magnitude of the current conducted by said electric valve means and including a phase shifting device for controlling the phase of the voltage impressed on said control member relative to the anode-cathode voltage, and means for preventing operation of said phase shifting device for a predetermined interval of time after the energization of said translating apparatus and for permitting progressive movement of said phase shifting device after the expiration of said interval in direct relation to the time of energization of said translating apparatus from said alternating current circuit.

14. In combination, an alternating current circuit, a load circuit, electric translating apparatus connected therebetween and comprising an electric valve means having an anode, a cathode and a control member for controlling the conductivity thereof, an excitation circuit for energizing said control member and comprising a phase shifting device of the rotary type for im-

- pressing on said control member an alternating voltage variable in phase with respect to the anode-cathode voltage of said electric valve means, means for operating said phase shifting device 5 and being biased to a position to maintain said electric valve means substantially nonconductive, means for preventing operation of said phase shifting device comprising an electroresponsive relay, and a control circuit comprising an electronic discharge device having an anode and a cathode which is energized from said alternating current circuit concurrently with said translating apparatus to control the energization of said electroresponsive relay.
- 10 15. In combination, an alternating current circuit, a load circuit, electric translating apparatus connected between said circuits and including an electric valve means having an anode, a cathode

and a control member, an excitation circuit for energizing said control member and comprising a phase shifting device for impressing on said control member an alternating voltage variable in phase with respect to the anode-cathode voltage of said electric valve means and having a movable member, means for biasing said member to a position to maintain said electric valve means nonconductive, means for rotating said member, a plurality of detent members arranged 10 to permit progressive movement of said member and comprising actuating coils, and a control circuit connected to be energized concurrently with said translating apparatus and including an electronic discharge device for selectively energizing said actuating coils in accordance with the period of energization of said translating apparatus. 15

ERNST F. W. ALEXANDERSON.
